UNITED STATES PATENT OFFICE.

HARRY MACKENZIE RIDGE, OF LONDON, ENGLAND.

ORE ROASTING OR DRYING FURNACE.

1,143,438.

Specification of Letters Patent. Patented June 15, 1915.

Application filed October 6, 1913. Serial No. 793,668.

To all whom it may concern:

Be it known that I, HARRY MACKENZIE RIDGE, a subject of the King of Great Britain, residing in London, England, and whose postoffice address is 62 London Wall, in the city of London, England, have invented certain new and useful Improvements in Ore Roasting or Drying Furnaces, of which the following is a specification.

10 This invention relates to multiple hearth furnaces for roasting or drying crushed or finely divided ores, concentrates, slimes or the like, wherein the ore is rabbled and caused to traverse the several hearths in 15 succession by the operation of a series of rabbles arms carried by a number of suitably spaced vertical shafts which extend downward or upward through the several tiers of hearths.

20 The primary object of the present invention is so to construct such furnaces that part thereof can be put out of operation, for the purpose of renewals or repairs, without shutting down the entire furnace. With 25 this object the rabbles and feed holes, and the discharge holes from the various hearths, are so arranged that while in normal working when the entire furnace is in operation, the ore or the like traverses the entire length 30 of each hearth in succession but should it be desired to cut out part of the furnace the rabbles shafts of that part are stopped and the ore, without other alteration than the opening or closing of one or more feed inlets 35 or discharge outlets will, by the action of the rabbles arms in operation, be caused to traverse in succession the several hearths of the other part of the furnace.

The invention is illustrated in the accompanying drawings wherein—

Figure 1 is a longitudinal section of a two-shaft three-tier roasting furnace embodying the present invention; Fig. 2 a transverse section on line 2—2 of Fig. 1, and Fig. 3 a 45 horizontal section on line 3—3 of Fig. 1; Fig. 4 is a longitudinal section of a four-shaft three-tier roasting furnace, Figs. 5 and 6 being sections on lines 5—5, 6—6 respectively of Fig. 4; Fig. 7 is a longitudinal 50 section of a double three-tier furnace having two parallel rows of rabbles shafts; Figs. 8, 9 and 10 are sections on lines 8—8, 9—9, 10—10 respectively of Fig. 7, Fig. 11 shows in detail one of the secondary discharge 55 openings provided in the hearths; and Fig. 12 shows in longitudinal section a furnace

constructed without drops between the sections.

The furnaces of Figs. 1 to 3 and 7 to 10 are shown as designed for being fired by producer gas, while the furnace of Figs. 4 to 6 is provided with a fire grate for the combustion of solid fuel. As, however, the firing arrangements form no part of the present invention no reference will herein-after be made to them, the description of the drawings being confined to those features which are considered to be novel in furnaces of this class.

Referring first to Figs. 1, 2 and 3 there are two rabbles shafts 1, 2 which extend vertically through the several hearths and are driven in opposite directions by any suitable means, each of these shafts having three rabbles arms 1^a, 1^b, 1^c and 2^a, 2^b, 2^c, the former set of arms being adapted to sweep the upper, middle and lower hearths of one half of the furnace, and the latter set of arms the upper, middle and lower hearths of the other half of the furnace.

As shown in Fig. 1 the three hearths are constructed with steps or drops at the central transverse plane of the furnace, these steps being arranged so that there will be a drop from the left hand or feed part 3^a of the upper hearth which is swept by the rabbles arm 1^a and to which the ore or the like is delivered through an approximately central feed inlet c, to the right hand part 4^a of the upper hearth, while in the middle hearth the drop is from the right hand part 4^b of the hearth to the left hand part 3^b, and in the lower hearth the drop is again reversed, being from the left hand part 3^c to the right hand part 4^c.

Further, the several rabbles are designed so that they will in succession cause the ore to be traversed alternately outward from the center to the edge and inward from the edge toward the center of the successive zones or parts of the hearths traversed by the ore, and this is true whether the whole furnace is in operation or whether either of the rabbles shafts 1, 2 is stopped and only half the furnace is in use. Thus, as indicated in the drawings, the ore fed through the inlet openings c on to the feed hearth 3^a is stirred by rabbles arm 1^a and gradually pushed outward from the center toward the ledge or step where it drops upon the right hand part 4^a of the upper hearth and is there worked inward by the rabbles arm 2^a until it reaches

the central discharge opening *e* through which it drops on to the right hand part *4^b* of the intermediate hearth. The rabble arm *2^b* works the ore outward from the center of this zone until it falls over the ledge on to the edge of the zone *3^b* where it is seized by the oppositely set rabbles of rabble arm *1^b*, by which it is worked in toward the center of the zone discharging through the central outlet *g* on to the left hand zone *3^c* of the lower hearth. The rabble arm sweeping this zone is designed to work the ore outward toward the edge of the same so that it falls over the ledge on to zone *4^c* where it is gradually swept inward by the rabble arm *2^c* to the approximately central discharge opening *h*. In addition to the central feed inlet *c* there is provided a second feed inlet *d* so placed that the ore when fed to the furnace through it will fall upon the outer edge of the zone *4^a*; and in addition to the various discharge openings above referred to there is a second discharge opening *f* in the upper hearth at or near the periphery of the zone *3^a*, a similar discharge opening *h* in the middle hearth at or near the periphery of the zone *4^b*, and a discharge opening *i* in the lower hearth at the edge of the zone *3^c*. One form of secondary discharge opening is illustrated in Fig. 11. This consists of a simple opening in the brickwork covered with a loose piece of firebrick which may easily be removed and replaced from the working doors at the side of the furnace.

The various inlet and discharge openings can be closed at will, the arrangement being such that when it is desired to cut off the right hand half of the furnace, the discharge openings *f*, *g* and *i* become operative so that the ore fed in through inlet *c* will successively traverse the zone *3^a* (from center to periphery), *3^b* (from periphery to center) and *3^c* (from center to periphery); while if it is desired to shut down the left half of the furnace the inlet *d* is used for feeding the ore on to the hearth zone *4^a* and the discharge openings *e*, *h* and *k* are operative, the ore traversing zones *4^a* (from periphery to center), *4^b* (from center to periphery) and *4^c* (from periphery to center).

It will be seen that while the central steps or drops in the several hearths facilitate the transference of the ore from one zone to the other, this can be effected without such drops in the hearth by means of the rabbles themselves.

There are two distinctly separate actions that may be performed by rabble arms, namely, a leveling action which spreads the ore so that it slowly but gradually moves forward when additional ore is fed onto the hearth, and a positive action which can be attained in various ways and especially by forming and arranging the rabbles so

that they will impart to the ore a movement or movements in desired directions. The latter action is only necessary when an ore is being treated which is only to remain in the furnace a comparatively short time. In Fig. 1, the rabble *1^a*, as shown, is used for moving the ore outward from the center of the rabble path to the periphery while rabble *2^a* is shown with two prongs which assist to move the ore inward from the periphery to the center of the rabble path. In certain cases, namely where the ore is to remain for a comparatively long time on each hearth and only to pass through the furnace slowly, these prongs would not be used, and in that case all of the same character tending to urge the ore spirally inward or outward with respect to the center of the respective rabble paths, or of kinds adapted to plow and stir up the ore without imparting thereto any definite direction of travel. Such rabbles are described and illustrated in U. S. Letters Patent No. 1,022,961, of April 9, 1912, and No. 1,068,518, of July 29, 1913. Accordingly, if the rabbles be all of one kind, or be such as will merely stir up the ore, a steady though slow progression of the ore can be maintained in the furnace, by reason of such rabbles continuing to level the ore as it is fed to the hearth and thereby causing the latter to travel slowly from one end to the other, and this progress may be assured or expedited by giving the hearth a tilt in the direction of travel in the known manner.

In the construction of Figs. 4, 5 and 6, the two intermediate rabble shafts 1 and 2 and hearth zones *3^a*, *3^b*, *3^c* and *4^a*, *4^b*, *4^c* correspond with the similarly designated shafts and hearth zones of Figs. 1, 2 and 3, but the rabble arms on these shafts may be all of the same kind and be designed either to move the ore in a positive manner from the centers of the zones toward their peripheries, as shown, or vice versa, or to perform a leveling action and thereby slowly but gradually move the ore forward as fresh ore is fed in. The outside shafts 5 and 6 are arranged in such proximity to the shafts 1, 2 respectively that the rabble arms on shafts 5 and 1 sweep over the same hearth zones, and the rabble arms of shafts 6 and 2 sweep over the same hearth zones.

The construction of the various rabble arms is such, and the inlet and discharge openings are so situated, that when the whole furnace is in use the ore fed through inlet openings *c* is spread out by the rabble arms *1^a*, *5^a* and subsequently traverses the upper hearth from left to right, the middle hearth from right to left and the lower hearth from left to right, the discharge openings *e*, *g*, *b* being operative.

As in the case of the construction shown

in Fig. 1, the transference of the ore from one side to the other of each hearth is insured by a central drop or step which, as shown, is from left to right in the upper and lower hearths and from right to left in the middle hearth.

If it is desired to shut down the right half of the furnace the shafts 2 and 6 are stopped and discharge openings *f*, *i* at or near the peripheries of the zones swept by the rabble arms 1^a, 1^c are uncovered so that the ore fed in at inlet *c* is discharged from the feed hearth through opening *f* to the intermediate hearth which is traversed from right to left and from which it is discharged through central opening *g* to the lower hearth the rabble arms of which gradually work it out to the discharge opening *i* at the periphery. Similarly if it is desired to use only the right half of the furnace, the shafts 5 and 1 are stopped and the fuel fed through inlet opening *d* to the center of the zone swept by the rabble arm 2^a by which it is worked gradually outward toward the periphery, the rabble arm 6^a acting in conjunction to drag the ore toward the central discharge opening *e* to the middle hearth. The rabble arms 6^b, 2^b, together cause the ore to be traversed along this hearth toward the left and discharge through the peripheral opening *h* (uncovered for this purpose) on to the lower hearth along which it gradually passes under the action of the rabbles 2^c, 6^c to the peripheral discharge opening *b*.

In the construction of Figs. 7, 8, 9 and 10 the furnace is double, there being two parallel rows of rabble shafts along the length of the furnace. As shown in the drawings the rabble arms are of the kind which tend to force the ore toward the periphery of the rabbling zones, and consequently a drop or step in each hearth is desirable in this case, in order to insure the proper progression of the ore along the hearths or to prevent it being transferred from one half to the other of the furnace when only one of these is in operation.

Assuming the whole of the furnace to be working, the ore fed through the inlet *c* to the upper hearth traverses the left hand half thereof until it falls over the step on the central transverse section of the furnace, whereupon the rabbles on the right hand half gradually work it toward the discharge opening *e*, whence it falls to the middle hearth traversing the latter from right to left and dropping through discharge hole *g* to the lower hearth, whence it passes to discharge opening *b*, the ore following the same course along the two sides of the furnace. If the four right hand shafts are stopped, the ore fed through inlet *c* passes downward from the upper hearth through opening *f*, traverses the middle hearth in the opposite

direction to opening *g* and the lower hearth again in the opposite direction to discharge opening *i*. Thus in this case the two additional discharge openings *f* and *i* are uncovered.

70

If the left hand half of the furnace is inoperative the ore is fed through inlet *d*, passing along the upper hearth from left to right, thence through discharge opening *e* to the middle hearth which it traverses from right to left, dropping through the opening *h* to the lower hearth which it traverses from left to right and from which it is discharged through outlet *b*.

The two sides of the double furnace may be quite symmetrical as shown, but whether this is so or not the two rows of shafts are at such a distance apart that the rabbling areas along the two sides do not overlap, the rabble arms being arranged to have just a clearance between their ends and the central line of the furnace. This arrangement secures the greatest rabbling area possible in a double furnace, and also insures that the rabbles of any section can be removed or started up again without getting foul of the rabbles of the corresponding section on the side of the furnace.

In addition to the steps or drops in the hearths shown on the central transverse section of the furnace, such drops may be provided at other places, and further by providing additional feed and discharge holes the furnace can be divided into more than four independently operative sections. For instance by the provision of auxiliary feed openings K and L and secondary discharge openings M, N, O, P, Q, the furnace may be divided into 8 independent sections, four on each side, a section at each end rabbled by the end shafts and two intermediate sections rabbled by each of the sets of three overlapping shafts.

It will be seen that in all these cases, whether the whole furnace is in use or only a part thereof, the direction of the travel of the ore is always the same along any given part of the furnace, and consequently no change requires to be made either in the direction of rotation of the rabble shafts, or in the set of the rabbles carried by the rabble arms.

While it is particularly desirable in the case of drying furnaces with large outputs to provide drops or steps in the hearths between the several rabbling zones so as to expedite the progress of the ore or the like along the hearths, it is to be understood that a substantially regular, although less rapid, feed of the ore from one zone or area swept by a set of rabbles to the next zone on any given hearth can be effected without such drops or steps by having as shown in Fig. 12 the adjacent rabble shafts of the two zones either fitted with rabbles of the two different

125

130

4
 characters already indicated, (that is to say the rabble arm or arms on one shaft carrying rabbles which are designed to push the ore positively outward toward the periphery of the rabbling zone and the rabbles on the other shaft designed to deflect any ore coming within their sweep inward toward the center of the zone, the two shafts being spaced so that the zones, do not overlap each other) or fitted with rabbles which, by spreading the ore fed to the zone, gradually cause it to be shifted along the hearth.

The several rabble shafts or groups of rabble shafts are driven from separate driving shafts which are arranged to be coupled or disconnected as required, according as the whole furnace or one or more sections of the same are operative.

I do not claim any novelty in the particular construction and arrangement of rabble arms here described as these are described and illustrated in the specifications of U. S. Patents Nos. 1,022,961 and 1,068,518, the novelty lying in the particular construction and arrangement of furnace hereinbefore described in which, however, such rabble arms may be efficiently employed to fulfil the purpose of the invention.

Having thus described the nature of the said invention and the best means I know of carrying the same into practical effect, I claim:-

1. In multiple hearth furnaces for roasting or drying crushed ores or the like, having two or more vertical shafts carrying arms which rabble the ore and cause it to traverse successive hearths in opposite directions, means whereby superimposed portions of said successive hearths and the relative rabble shaft or shafts and rabble arms can be put out of action without interfering with the working of the other part.

2. In multiple hearth furnaces for roasting or drying crushed ores or the like having two or more vertical shafts carrying arms which rabble the ore and cause it to traverse successive hearths in opposite directions, means whereby superimposed portions of said successive hearths can be put out of action without interfering with the working of the other part comprising auxiliary closable discharge holes in the hearths above the lowest at or near the transverse plane or planes dividing the separately operable portions substantially as hereinbefore described.

3. In multiple hearth furnaces for roast-

ing or drying crushed ores or the like having two or more vertical shafts carrying arms which rabble the ore and cause it to traverse successive hearths in opposite directions, means whereby one part of the furnace can be put out of action without interfering with the working of the other part, comprising hearths constructed with steps or drops on the transverse plane dividing the furnace into the sections capable of being put out of operation and auxiliary closable discharge holes at or near the same transverse plane in the hearths above the lowest, substantially as hereinbefore described.

4. A furnace for roasting or drying crushed ore or the like having a plurality of separable rabbling zones arranged in the same plane and means for effecting progression of the ore from one rabbling zone to the next, substantially as hereinbefore described.

5. A furnace for roasting or drying crushed ore or the like having a plurality of separate rabbling zones arranged in the same plane, and a rabble arm in each zone having rabbles thereon adapted to spread the ore in its zone and feed it forward to the next one, substantially as hereinbefore described.

6. In a furnace for roasting or drying crushed ores or the like, the combination with one vertical shaft having rabble arms adapted to spread or push the ore outward toward the periphery of the zone swept by its rabbles, of a second vertical shaft having rabble arms adapted to deflect or draw inwardly any ore coming within the periphery of its zone, said shafts being spaced at such a distance that the zones swept by their respective rabble arms do not overlap, substantially as hereinbefore described.

7. A furnace for roasting or drying crushed ores or the like, constructed with two rows of vertical rabble shafts having rabble arms thereon, so arranged that the rabbling zones of each row just fail to overlap the corresponding zones of the other.

In testimony whereof I have signed my name to this specification in the presence of two subscribing witnesses.

HARRY MACKENZIE RIDGE.
